UNITED STATES PATENT OFFICE.

CHARLES H. BROWN, OF BRECKENRIDGE, TEXAS.

UNDERREAMER.

Application filed October 7, 1925. Serial No. 61,119.

This invention appertains to wells and more particularly to a novel under reamer.

The primary object of the invention is to provide an improved under reamer which

5 will effectively enlarge the hole below the well with little danger of losing the cutters and which is so constructed as to underream the hole rapidly and expeditiously with a minimum amount of wear on the tool.

10 Another object of the invention is the provision of novel means for taking up the wear in such a manner that all danger of operating the tool after long use is eliminated, the construction of the various parts 15 of the tool allowing a maximum amount of actual wear to take place before making it necessary to repair the tool in any way.

A further object of the invention is to provide novel means for constructing the 20 under reamer in such a manner that a high grade of materials can be used in the construction thereof and still permit a tool to be placed upon the market at a very reasonable price.

25 A further object of the invention is to provide an under reamer embodying novel cutters which are of such size that the same may be drop forged so that they are almost to size thereby eliminating considerable expensive machine work thereon thus reducing 30 the cost and upkeep of the tool.

A further object of the invention is the provision of novel cutters having a circular shape on the inside so that the material close 35 to the same can be worked out to the cutting edge by hammering on the inside thereof thus eliminating the necessity of keeping the cutters in the fire a relatively long length of time during the dressing thereof and thus preventing injury thereto, the cutters permitting a relatively great quantity of material 40 to be worn away from the same before the cutters become rendered unfit for use.

A further object of the invention is the 45 provision of novel means for mounting the cutters in place and novel means for raising the cutters relative to one another whereby the loss of the cutters is precluded.

A still further object of the invention is 50 the provision of novel means for moving the cutters to their working and non-working positions, so as to permit the expeditious removal and placing of the tool in position.

A further object of the invention is the 55 provision of novel means for holding the cutters in operative position, whereby the

same will be held firmly against movement and whereby a minimum amount of wear will take place on the said holding means.

A still further object of the invention is 60 to provide a novel under reamer of the above character which will be durable and efficient in use, one that will be simple and easy to manufacture and one which can be placed upon the market at a reasonable cost. 65

With these and other objects in view, the invention consists in the novel construction, arrangement and formation of parts, as will be hereinafter more specifically described, claimed, and illustrated in the accompanying drawings, in which drawings:

Figure 1 is a longitudinal section through the upper end of the under reamer,

Figure 1^a is a longitudinal section through the lower portion of one form of the improved under reamer, 75

Figure 2 is a bottom plan view of the improved under reamer showing the cutting blades in their extended operative position in full lines, and in their collapsed positions 80 in dotted lines,

Figure 3 is a detail section through the under reamer taken on the line 3—3 of Figure 1^a illustrating the means of mounting the blades in place, 85

Figure 4 is a detail section taken on the line 4—4 of Figure 1^a illustrating the method of holding the blades and hanging means in place in the body of the under reamer, 90

Figure 5 is a detail section taken on the line 5—5 of Figure 1^a looking in the direction of the arrows showing the mandrel in cross section,

Figure 6 is a detail section taken on the line 6—6 of Figure 1 looking in the direction of the arrows showing the formation of the upper end of the body of the under reamer and the mandrel, 95

Figure 7 is a detail section taken on the line 7—7 of Figure 1 looking in the direction of the arrows showing the novel releasing means, 100

Figure 8 is a longitudinal section through a slightly modified form of the tool, 105

Figure 9 is a detail horizontal section through the same taken on the line 9—9 of Figure 8 looking in the direction of the arrows showing the releasing means for the modified type of the tool, 110

Figure 10 is a bottom plan view of the tool of the modified type showing the cutting

blades in their extended position in full lines and in their collapsed condition in dotted lines.

Figure 11 is a detail horizontal section taken on the line 11—11 of Figure 8 looking in the direction of the arrows, showing the novel means for holding the blades in place.

Figure 12 is a longitudinal section through a still further modified type of the tool, 10 Figure 13 is a detail horizontal section taken on the line 13—13 of Figure 12 looking in the direction of the arrows illustrating the releasing means,

Figure 14 is a horizontal section taken on the line 14—14 of Figure 12 looking in the direction of the arrows showing the means for holding the operating shank in place, and

Figure 15 is a detail perspective view of 20 one of the novel arms of the releasing device for said cutting blades.

Referring to the drawings in detail, wherein similar reference characters designate corresponding parts throughout the several views the letter A generally indicates the improved under reamer which comprises a body 15 having the usual shank 16 formed on the upper end thereof with the means 17 for permitting the connection of the tool 30 with the well rod.

The body 15 is preferably of a circular shape in cross section and is provided with a longitudinally extending bore 18 having a longitudinally extending slot 19 communicating therewith. This slot terminates short of the lower end of the body and extends substantially to the upper end thereof. The body 15 adjacent to the lower end thereof is provided with internal threads 20 for the 40 reception of the lower auxiliary body 21 which is provided with a shoulder 22 adjacent to its upper end for abutting engagement with the lower end of the main body 15. The lower auxiliary body 21 is provided with a bore 23 which opens out the upper end thereof and communicates with the bore 18 of the main body 15. As shown the auxiliary lower body 21 adjacent to its lower end is provided with a hollow circular 50 shaped head 24 which defines an internal annular shoulder 25 having the axial opening 26 therethrough, the purpose of which will be hereinafter more fully described. Slidably mounted within the bore 18 of the main body 15, and the bore 23 of the auxiliary lower body 21 and the opening 26 is a cylindrical rod or mandrel 27 which extends below the lower end of the head 24 and terminates substantially in the upper end 60 of the bore 18. The mandrel adjacent to its lower end is provided with an integral stop shoulder 28 against which is fitted the mandrel cone 29 provided for adjusting the position of the novel cutter blades 30, which 65 are three in number and which will be here-

inafter more fully described. The extreme lower end of the said mandrel 27 is threaded for the reception of a retaining nut 31, which is utilized for holding the mandrel cone in position on the said mandrel and the lower end of the rod can have connected thereto to a suitable clevis (not shown) for pulling the mandrel down to a blade releasing position when the tool is being initially inserted within the well pipe or casing. The mandrel and consequently the mandrel cone 29 is normally held in a raised position by a relatively heavy expansion spring 32 which is coiled about the mandrel 27, the lower end of the said spring engaging the internal shoulder 25 and a suitable collar 33 held on the mandrel by retaining and locking nuts 34.

Each of the blades 30 include substantially parallel shank portions 35 having notches 36 in their inner faces adjacent to the upper end thereof defining upper and lower shoulders for a purpose, which will be hereinafter more fully described. Below the parallel shanks 35, the blades are provided with substantially arcuate body portions 37 which project slightly beyond the shanks defining stop shoulders 38 which are adapted to engage the lower edge of the head 24 when the blades are in their operative position. The lower ends of the blade bodies 37 are provided with projecting cutting portions 39 and the inner faces of the blades are arcuate shaped as indicated by the reference character 40. The inner faces of the shank 35 and the body 37 above the portions 39 and 40 are provided with inclined faces 41 which are adapted to be engaged by the cone 29 for forcing the blades apart and holding the same in their operative position against the said head 24. Particular attention is called to the design of these cutters and the way which they set into the head and the manner in which the cone comes up inside of the cutters to hold them in position. It can be seen that all of these parts are parts of a circle and that the said parts of the circle are all concentric and therefore the parts are all self centering and that any wear on the cutters or inside of the head is immediately taken up by the cone pressing on the inner faces of the cutters. This connection is to also hold the cutters out to gage and any wear occurs on the shanks of the cutters and the inner surface of the head causes the projecting parts of the cutters to push out to gage the hole and instead of an old cutter having to be dressed farther and farther outward as has been the case in all other under reamers, these cutters have to be hammered a smaller amount to bring them to gage when they are old and when they are new.

In under reaming when the blow strikes the point of the cutters against the shoulder of the hole below the well casing, the result-

ant forces drive the cutters against the shoulders of the head and also the cutting edges try to dodge toward the center of the hole. This last force is taken up by the 5 inner surface of the cutters resting on the cone and as these cutters receive these forces on opposite sides of the cone it will be seen that the cone is supported in all directions and at all times. It will be seen that the 10 heavy mandrel spring 32 holds the cone in between the cutters, seating them so tightly that the tool closely approximates a solid one in its rigidity. The use of the three cutters, instead of the conventional two cutters, 15 eliminates a great deal of trouble herebefore experienced in under reaming such as loss of cutters, which are mainly caused by what is known as key seated holes. The blades fitting relatively close together permit 20 the substantial entire area of the hole to be acted on at all times thus allowing the hole to be cut as fast as the cutters are driven.

In order to hold the cutters 30 in position I provide a novel retaining ring 42 which 25 is provided with an annular groove 43 defining a lower shoulder 44 which fits within the notches 36 formed in the shanks of the cutting blades and further provided with lugs 44^b interfitting with the shanks 35, as 30 clearly shown in Figure 3 of the drawings. The retaining ring is in turn held in place by the use of suitable retaining pins 45 which are inserted through suitable openings in the head 24 directly below the flange 46 formed 35 on the retaining ring. The pins 45 engage the retaining flange to hold the same tightly in place against the internal shoulder 25.

To change cutters it is merely necessary to drive the retaining pins 45 out from in 40 front of the retaining ring thereby enabling the retaining ring to slide down when the mandrel is pulled down to its dotted position at which time the old cutters can be removed and a sharp set put on.

45 In order to release the cutters 30 from operative position a novel releasing slide block 50 is provided. This release slide block 50 is mounted directly within the upper end of the bore 18 of the upper body 15 and is provided with a projecting rib 51 which is adapted to normally extend through the longitudinally extending slot 19. The outer end of the rib 51 is inclined as at 52 and the upper edge of the 55 rib is oppositely inclined as at 53 and further provided with a lower inclined wall 52^b for a purpose, which will be hereinafter more fully described. A socket 54 is formed in the extreme lower end of the slide release 60 block 50 and is adapted to receive the upper end of the mandrel 27, a cushioning spring 55 being coiled about said mandrel engaging the lower end of the slide block and the upper locking nut 34. The inner face of 65 the release slide block 50 is provided with

a shoulder 56 which is adapted to normally engage a rigid release block 57 which is held in position in any suitable manner such as by welding or the like as indicated by the reference character 58. When the improved 70 reamer is to be inserted within the well casing the mandrel 27 can be pulled down in any desired way and the release slide block 50 is moved down therewith and held in its lowered position, with the rib 51 flush with 75 the outer face of the body by a suitable retaining ring (not shown). This will hold the cutters 30 in a lowered collapsed condition within the circumference of the head 24 of the body. As the tool is inserted with 80 in the well casing the retaining ring (not shown) will be stripped off the body and the expansion spring 32 will normally tend to raise the mandrel cone 29 and the release block 50 to a raised position. As soon as the 85 tool protrudes beyond the lower end of the well pipe casing, the blades will assume the position shown in Figure 1^a and be held in place by the cone 29 and the release slide block 50 will be positioned at one side of the 90 rigid release block 57 as shown in Figure 1. The tool can now be used in the ordinary way and when it is desired to remove the same from the casing the tool is pulled up and the inclined face 53 of the rib 51 will 95 strike against the lower edge of the well casing which will force the slide block down carrying the mandrel 27 and the cone 29 therewith. As soon as the cone is forced below the cutters, the cutters will be permitted to rock inwardly and as the slide block 50 rides below the lower edge of the rigid release block 57 the said release slide block 50 will rock inwardly owing to the 100 inclined face 53 and the entire tool can be 105 drawn into the well casing and out of the same. By having the block 50 function as just described, the operation is positive, and to assure the releasing device being fool-proof in every respect the lower inclined 110 wall 52^b is arranged to engage the lower wall of the slot 19 when the slide block has been forced downwardly a predetermined 115 distance to engage under block 57, and thus the block is bodily movable either by the engagement of the inclined wall 53 with the bottom of the casing or by the engagement of the inclined wall 52^b with the lower wall of the slot should it happen that the block 50 is pushed down the required distance, and 120 thus the cooperation between the wall 52^b and wall of the slot acts in the capacity of a safety device.

In Figures 8 to 11 inclusive I have shown a slightly modified form of my invention in which the tool embodies the upper body 60 having the bore 61 opening out through its lower end which receives the lower body 62 having the circular head 63 defining the angular inner shoulder 64. The mandrel 65 125

extends through the body 62 into the bore 61 of the upper body 60 and the lower end of the mandrel has secured thereto the mandrel cone 66 which embodies an upper tapered portion 67 for engaging the shanks 68 of the blades 70 and a lowered tapered portion 71 for engaging the tapered inner faces of the body portions of said blades. These blades are constructed substantially the same as the blades in preferred form with the exception of the shanks thereof which are provided with diametrically alined slots 72 through which extends a diametrically extending holding rod 73 held in place by removable pins 74 which extend through the head 63. The mandrel 65 is slotted at a point between its end as at 75 for the reception of the said rod 73. The upper end is provided with a cap nut 76 against which a washer 77 is placed. A relatively heavy expansion spring 78 is coiled about the mandrel and rests upon the shoulder 64 and the said washer normally holding the cone 66 in a raised position and the cutter 70 in engagement with the head.

Arranged within the bore 61 above the upper end of the mandrel 65 is a releasing slide block 80 having the radially extending rib 81 which protrudes through a slot 82 formed in the body 61. The lower end of the releasing slide block 80 is provided with a socket for the reception of the cap nut 77 and the inner face of said slide block is provided with a shoulder 83 which is adapted to normally engage the rigid release block 84 secured within the bore in any desired way. This under reamer is operated in the same manner as the under reamer herebefore described and it is to be noted that when it is desired to withdraw the tool through the casing, that the tool is drawn upwardly until the rib 81 catches under the lower edge of the well casing which will force the said releasing slide block downward into engagement with the mandrel 65 forcing the cone 67 out of engagement with the blades which will permit the blade to swing inward by gravity to a releasing position at which time the block 80 will rock within the bore 61 allowing the rib 81 to pass by the said casing and thus permit the tool to be drawn through the same.

In Figures 12 to 15 inclusive I have shown a still further modified form of the invention in which I have provided a novel releasing mechanism for the blades. In this form the body 90 is provided with diametrically disposed slots 91 and a cup 92 is slidably mounted within the bore 93 of the body. Arranged centrally within the bore is a depending lip 94 on each side of which is positioned the releasing arms 95 and 96. These releasing arms 95 and 96 are rockably mounted upon a common pivot pin 97 carried by the cup 92. The upper ends of the

releasing arms 95 and 96 are provided with ribs 98 which protrude through the slots 91 formed in the said body. The upper ends of these ribs 98 are provided with inclined faces 99 for permitting the same to slip by the casing when the tool is being withdrawn from the well. In practically all other respects, the tool is the same as the tool shown in Figures 8 to 11 inclusive and it is to be noted that as the tool is withdrawn from the well casing that the lower edge of the casing will engage the ribs 99 forcing the cup 92 inward into contact with the mandrel thus forcing the same downward allowing the collapsing of the blade.

Changes in details may be made without departing from the spirit or the scope of this invention, but:

What I claim as new is:

1. An under reamer comprising a body, a plurality of arcuate cutters concentrically arranged in the lower end of the body mounted for rocking movement toward and away from the axial center of the body, a mandrel slidably mounted in the body, an adjusting cone carried by the mandrel adapted to engage the inner faces of the cutters for normally holding the same in rigid contact with the body to prevent movement thereof when the reamer is in use, a relatively heavy expansion spring coiled about the mandrel normally holding the cone in engagement with the cutters, a releasing slide block mounted within the upper end of the body, the body being provided with a longitudinally extending slot communicating with the interior of the body, a rib formed on the releasing slide block adapted to project through said slot, the inner end of the slide block being adapted to engage the upper end of the mandrel, a shoulder formed on the inner face of the releasing slide block at the lower end thereof, a rigid block normally engaging said shoulder, and adapted to engage the upper end of the slide block, when the slide block is forced downward to move the cone to cutter releasing position.

2. An under reamer comprising a hollow body, a plurality of arcuate cutters concentrically arranged rockably mounted in the lower end of the body and adapted to protrude therefrom, a mandrel slidably mounted axially within the body, a mandrel cone secured to the mandrel adapted to engage the inner surfaces of said cutters for holding the cutters in engagement with the lower end of the body in an extended operative cutting position, an expansion spring coiled about the mandrel normally holding the cone in its raised position in engagement with the cutters, a releasing slide block rockably mounted on the upper end of the mandrel having a rib adapted to project normally beyond the outer side face of the body having an inclined upper edge, and a shoulder at its lower

inner face, a rigid block adapted to engage the shoulder when the block is in its raised position and the upper end of the block when the same is in its lowered position and the 5 cone below the cutters.

3. An under reamer comprising a body provided with a straight bore having an annular shoulder, a mandrel extending through the bore and said shoulder, a retaining ring 10 mounted upon the mandrel, means detachably holding the ring in place, cutters rockably mounted upon the ring, a cone mounted upon the mandrel for engagement with the cutters to hold the same in an adjusted position, adjusting nuts carried by the upper end 15 of the mandrel, an expansion spring coiled about the mandrel engaging said nut and shoulder, a releasing slide block carried by the upper end of the body having a rib normally 20 projecting beyond the body and a shoulder on the inner lower end thereof, a socket formed in the lower end of the slide block to receive the upper end of the mandrel, a cushioning spring about said mandrel engaging the slide block, and a rigid block mounted within said body for engaging a slide block when the same is in its 25 raised position and for engaging the upper end of the slide block when the same is in a lowered position.

4. An under reamer comprising a body provided with a straight bore having annular shoulders, a mandrel extending through the bore and said shoulders, a retaining ring 30 mounted upon the mandrel, means detachably holding the ring in place, cutters rockably mounted upon the ring, a cone mounted upon the mandrel for engagement with the cutters to hold the same in an expanded position, adjusting nuts carried by the upper 35 end of the mandrel, an expansion spring coiled about the mandrel engaging said nuts and shoulders and means for collapsing the cutters.

45 5. An under reamer comprising a body, cutters rockably mounted upon the lower end of the body, a mandrel slidably carried by the body, a cone on the lower end of the mandrel for engaging the cutters for normally holding the same in an extended position in rigid contact with the body, an expansion spring coiled about the mandrel normally holding the same in a raised position and the cone in engagement with the cutters, 50 55 a releasing slide block mounted within the upper end of the body, the body being provided with a cut out portion communicating with the interior of the body, said block having a portion thereon adapted to extend through said cut out portion, the inner end

of the slide block adapted to engage the upper end of the mandrel, a shoulder formed on the inner face of the slide block at the lower end thereof, a rigid block normally engaging said shoulder, and adapted to engage the upper end of the slide block when the slide block is forced downward to move the cone to cutter releasing position. 65

6. In combination with a body, a collapsible cutter structure carried thereby, means controlling the movement of the cutters comprising a plunger having expansible engagement with said cutters, a stationary block carried by the body, and a movable block having a plurality of inclined walls for operative engagement with the well casing and having a yieldable connection with said plunger for giving movements thereto. 70 75

7. An underreamer comprising a body, cutters adjustably supported by the body, a plunger for adjusting and rigidly holding the cutters in adjusted position, a mandrel connected to the plunger and yieldably and slidably supported by said body, and a slidably mounted, releasable block yieldingly 80 85 engaging the mandrel in its initial movement and rigidly engaging the mandrel in its final movement.

8. An underreamer comprising, in combination, a body, a plurality of cutters and a retainer connected together as a unit for adjustments and placement within the body, a mandrel structure controlling the relative movements of said cutters, said body provided with an inclined shoulder, and a block 90 95 slidably supported by the body and having suitably placed inclined walls adapted to engage with a well casing for giving movements to the block for displacing the same under said shoulder, said block having an operative engagement with the mandrel. 100

9. An underreamer comprising, in combination, a body, a plurality of cutters and a retainer connected together as a unit for adjustments and placement within the body, a mandrel structure controlling the relative movements of said cutters, said body provided with an inclined shoulder and a slot contiguous thereto, a block slidably supported by the body and having suitably placed inclined walls adapted to incline with a well casing for giving movements to the block or with a wall of said slot for displacing the block under said shoulder, said block having a loose connection with the mandrel in its initial movement and a rigid connection therewith in its subsequent movement. 105 110 115

In testimony whereof I affix my signature.

CHARLES H. BROWN.
